UNITED STATES PATENT OFFICE.

DAVID ROSEN, OF CAMDEN, NEW JERSEY, ASSIGNOR OF ONE-FOURTH TO CLARENCE B. GROFF, OF HADDON HEIGHTS, NEW JERSEY, AND ONE-FOURTH TO JOSEPH TAYLOR, OF CAMDEN, NEW JERSEY.

GARMENT-SUPPORTER.

1,206,470.

Specification of Letters Patent. Patented Nov. 28, 1916.

Application filed April 18, 1915. Serial No. 21,002.

To all whom it may concern:

Be it known that I, DAVID ROSEN, a citizen of the United States, residing in Camden, New Jersey, have invented certain Improvements in Garment-Supporters, of which the following is a specification.

The object of my invention is to so construct a lady's coat or waist hanger that the same will properly support the bust portion 10 of the garment when in use but can be collapsed so that it will occupy but a minimum amount of space when not in use. This object I attain in the manner hereinafter set forth, reference being had to the accompanying drawings, in which—

Figure 1 is a front view of a coat or waist hanger showing the same in the collapsed condition; Fig. 2 is a transverse section of the same; Fig. 3 is a similar section showing 20 the supporter expanded, as when applied to the coat or waist; Fig. 4 is an enlarged sectional view of a swivel connection between the hanger and the supporting hook at the top of the same, and Fig. 5 is a sectional 25 view illustrating a modification of one of the features of my invention.

In the drawing, 1 and 2 represent, respectively, the top and bottom bars of the hanger which are connected by a series of flexible 30 strips 3, preferably of spring steel, the ends of these strips being secured to the top and bottom bars in any appropriate way. Extending through the top bar 1 of the hanger is a central vertical opening 4 and intersecting this opening is a transverse opening 5, as shown in Figs. 2 and 3. Secured to the lower bar 2 of the hanger is a vertical rod 6 which passes through the central vertical opening 4 in the top bar of the hanger and 40 has, at its upper end, a suspension hook 7, preferably connected to the rod 6 by a swivel joint such as hereinafter described.

The rod 6 is notched at a number of different points throughout its length, as 45 shown for instance at 8, and upon the front of the top bar 1 of the hanger is mounted an elastic pawl 9, the free end of which plays in the transverse opening 5 and has a normal tendency to engage the notches 8 in the rod 6. The pawl 9 is provided with a finger 10 whereby it may be pressed forwardly so as to release it from engagement with a notched portion of the rod 6 and thus permit readjustment of the latter. The hanger be-

ing applied to the coat or waist while the 55 parts are in the position shown in Fig. 2, the top and bottom bars are then caused to approach each other and the elastic strips 3 connecting said bars will thus be projected, as shown in Fig. 3, so as to fill the bust portion 60 of the coat or waist and hence properly support the same, the bars 1 and 2 being retained in this position by reason of the engagement of the pawl 9 with one of the notches in the bar 6. The provision of a series of these notches permits a number of different adjustments of the top and bottom bars 1 and 2 in respect to one another and a consequent difference in the extent of projection 65 of the strips 3 so as to accommodate 70 them to garments of different sizes.

In order to provide a swivel connection between the suspension hook 7 at the top of the hanger and the adjusting rod 6, I preferably secure to one of said members of the 75 hanger a sleeve 11 which receives the other member of the hanger but permits the latter to rotate freely within it, and in order to prevent separation of the members of the hanger the rotating member, in this instance 80 the member 7, has one or more grooves 12 formed therein, which grooves are engaged by internal ribs 13 in the sleeve 11, these ribs being preferably formed by indenting 85 the metal of which the sleeve is composed, as shown in Fig. 4.

While I prefer to adopt the notched rod and pawl as a means of retaining the top and bottom bars of the hanger in different 90 vertical relations to one another, other means than this may be employed within the scope 95 of my invention, for instance, as shown in Fig. 5, the top bar may carry a nut 14 for the reception of a clamping screw 15 which bears upon a plain rod 6^a and serves to retain the bar 1 in different positions of adjustment on said rod.

I claim:

1. The combination, in a garment hanger, of upper and lower bars, flexible strips connecting the same, said upper bar having intersecting vertical and transverse openings therein, a notched rod passing through said vertical opening, and a pawl whose free end plays in the transverse opening and engages 105 the notches of the rod.

2. The combination, in a garment hanger, of upper and lower bars, flexible strips con-

necting the same, an adjusting rod for retaining said upper and lower bars in different vertical relations to one another, a suspension hook, and a swivel connection between the same and the upper end of said adjusting rod.

3. The combination, in a garment hanger, of upper and lower bars, flexible strips connecting the same, an adjusting rod for retaining said upper and lower bars in different vertical relations to one another, a suspension hook, and a swivel connection between the same and the upper end of said

adjusting rod, said swivel connection comprising a sleeve secured to one of said members and surrounding a portion of the other member, the latter being grooved and the sleeve being indented so as to form thereon an internal rib for engaging said groove. 15

In testimony whereof, I have signed my name to this specification, in the presence of two subscribing witnesses.

DAVID ROSEN.
